(57) **CLAIM**

The ornamental design for racquets for games, as shown and described.

DESCRIPTION

1. Racquet for games
2. Racquet for games
3. Racquet for games

Fig. 3.1 is a left side view of a racquet for games, according to the novel design;

Fig. 3.2 is a front view thereof;

Fig. 3.3 is a right view thereof;

Fig. 3.4 is a back view thereof;

Fig. 3.5 is a top view thereof;

Fig. 3.6 is a front perspective view thereof; and

Fig. 3.7 is a bottom plan view thereof.

Broken lines in the reproductions show matter which does not form part of the claimed designs and for which protection is not sought.

1 Claim, 7 Drawing Sheets
